(57) **CLAIM**

The ornamental design for a vehicular power converter, as shown and described.

DESCRIPTION

FIG. 1 is a perspective view of a vehicular power converter, showing my new design;

FIG. 2 is a front elevational view thereof;

FIG. 3 is a rear elevational view thereof;

FIG. 4 is a left elevational view thereof, wherein the right elevational view of the vehicular power converter is a mirror image of FIG. 4;

FIG. 5 is top plan view thereof;

FIG. 6 is a bottom plan view thereof; and,

FIG. 7 is a perspective view of the vehicular power converter wherein the outlet cover is shown in a closed position, and a power cord and plug are shown for illustrative purposes only and form no part of the claimed design.
